(57) **CLAIM**

The ornamental design for a shake siding panel, as shown and described.

DESCRIPTION

FIG. 1 is a perspective environmental view of a shake siding panel having a contoured lower edge. The shake siding panel, adjacent panels illustrating an environment for the shake siding panel, and an upper interlock. The phantom lines form no part of the claimed invention.

FIG. 2 is a front view of the shake siding panel.

FIG. 3 is a side view of the shake siding panel illustrating the contoured lower edge slanting inwardly from front face and upwardly towards a lower interlocking lip.

FIG. 4 is a top view of the shake siding panel shown in FIG. 2.

FIG. 5 is bottom view of the shake siding panel shown in FIG. 2; and,

FIG. 6 is rear view of the shake siding panel with the contoured lower edge extending below the lower interlocking lip.
